UNITED STATES PATENT OFFICE

2,581,861

ELECTRICAL APPARATUS

Carl A. P. Johnson, North Quincy, and Archie T. Morrison, South Braintree, Mass., assignors to S. H. Couch Company, Inc., North Quincy, Mass., a corporation of Massachusetts

Application February 9, 1950, Serial No. 143,252

2 Claims. (Cl. 200—51.1)

1

The present invention relates to a co-operating electric plug and receptacle which may be used in a fixed position or on a portable line or cable and is particularly designed for use in connection with special annunciator systems as, for instance, the kind generally used in hospitals for bed patients in calling for aid and signaling the attention of attendants or nurses.

In most of such hospital systems the patient in the bed has an electric cord near the bed which ends in a push button. The cord is usually plugged into a wall receptacle which has electrical connections to a number of places. When the patient wishes to call or signal, he presses the push button and visual and audible signals are produced at various places as, for instance, in the nurses' office, in front of the patient's door (where a light usually appears), and in several other places.

In order to be assured that the patient may at all times signal for aid, special means have been employed to make certain that the circuit always remains in working order so that when the patient presses the button, the proper signals will be produced. One common difficulty experienced in the past has been that the cords and plugs come out or are pulled out of their receptacles with the result that when the patient signals, the cord is dead and no electrical connections are made. Various methods and devices have been employed in the past for producing a signal merely when the plug comes out of the receptacles, which is the general subject matter of the present invention, so that the attendants know when the plug has been disconnected.

The present invention has advantages over the devices in the prior art inasmuch as no rotating elements are used and the device is simply constructed and of a fool-proof nature.

The present invention is a division of our co-pending application, Serial No. 597,472, filed June 4, 1945, Patent No. 2,500,184, in which the present form of invention was shown. The difference between the present modification and that described and claimed in the original case is that the action is positive in the operation of the switch effected entirely by the insertion or the removal of the plug in the receptacle. The removal of the plug acts in a positive manner to pull out the connecting jack element so that the circuit will be completed.

The invention will be more fully understood from the specification annexed hereto when taken on connection with the drawing in which the figure shows a broken section through the receptacle and part of the plug.

2

In the arrangement indicated in the figure, the individual receptors and the connector terminals are substantially the same as in the modification of Figure 2 of our co-pending case which has matured into said patent. In the present case, however, the spring fingers 32, 32 are turned in the reverse direction outwardly in the direction of the front face of the receptacle. The jack 33 has an insulating body portion 34 to which a conductive member 35 is attached. This member 35 is provided with a cylindrical conducting portion 36 of the same diameter as a similar portion 37 of the insulating part of the jack. At one end of the conductive member 35 there extends an axially located pin element 38 and at the other end of the electrical conductive member 35 there extends a projecting pin member 39 which anchors firmly the member 35 to the insulating portion of the jack.

20 The pin 38 fits freely for longitudinal motion in a hole 39' in the wall 40 at the end of the receptacle case. The other end of the jack is formed with a long insulating neck portion 41 joined to the central insulating cylinder 37 in a small shoulder 42. The neck portion 41 of the jack has a sliding fit in the hole 42' in the front plate of the receptacle. This hole is just large enough to permit free motion of the neck portion 41 until the shoulder 42 comes to rest on the inside surface 30 43 of the insulating plate member 44' when the plug is moved to the right from the position as shown in the figure.

The front end of the jack 33 is provided with a rounded head member 44 which has an arcuately shaped or gouged out neck portion 45 in which the curved doubled prong spring having prongs 46 fit. This spring is riveted to the plug member 47 at the end wall of the cavity 48 in the face of the plug member. A pin 49, positioned centrally between the prongs 46 in the cavity 48, is aligned to engage a centrally located recess in the end of the rounded head 44. The spring prongs 46 and its support has a section of a general reversed C shape. The pin 49 will ensure the plug being pulled out axially with the jack 33. The spring prongs 46 are made sufficiently strong so that the jack 33 is firmly gripped when the plug is put in place. If the plug is accidentally removed or removed on purpose, the grip of the spring fingers 46 on the jack 33 will make certain that the jack is pulled outward with the receptacle until the shoulder 42 comes up against the face 43 of the insulating wall 44. When this occurs, a circuit will be completed through the conducting cylinder 36

and the annunciator circuit will function in the usual manner.

The spring fingers 32 should have sufficient pressure on the jack member so that it will remain in whatever position it is placed. For this purpose both the insulating section 37 and the conductive section 36 may be provided with circular grooves 50 and 51 respectively on the face of the jack to aid in retaining the jack in one of its two positions. In this way if the plug is removed, the jack will remain in its outward position until restored manually by pressing the end of the head 44. If the plug is returned to its position in the socket, the jack will be pushed inward, breaking the circuit and at the same time the spring fingers 46 will come to rest in the arcuate sides of the collar portion of the head.

The invention has been described in connection with a receptacle and plug showing five circuits. It is obvious that not all of these need be used and that the plug and receptacle may be used or designed with one or more receptors and connectors although, because of symmetry, the use of a plurality of receptacles is preferable.

Having now described our invention, we claim:

1. A plug and receptacle assembly comprising a receptacle casing having a plurality of electrical receptor members positioned about a central longitudinal axis of the receptacle, a plurality of spring arms also positioned about and extending longitudinally with said longitudinal axis of said receptacle, said spring arms being electrically connected to said electrical receptors, a connecting jack having a flanged end with a concave groove behind the end extending all around the jack and having insulating sections and conductive sections along portions of its surface and having longitudinal axis parallel to the central axis of said receptacle, means supporting said jack in said position for reciprocal motion confined to its longitudinal axis, a plug member having spring prongs with inwardly concave ends adapted to engage in the

groove behind the head of said jack when the plug pins are inserted in the receptacle, said means connecting said plug and jack together whereby when said plug is removed, the jack will be moved outward to a circuit closing position.

2. A plug and receptacle assembly comprising a receptacle casing having a plurality of electrical receptor members positioned about a central longitudinal axis of the receptacle, a plurality of spring arms also positioned about and extending longitudinally with said longitudinal axis of said receptacle, said spring arms being electrically connected to said electrical receptors, a connecting jack having insulating sections and conductive sections along portions of its surface and having longitudinal axis parallel to the central axis of said receptacle, means supporting said jack in said position for reciprocal motion, a plug member having means adapted to engage said jack when the plug pins are inserted in the receptacle, said means comprising a recessed neck portion adjacent the forward end of the jack and spring gripping means mounted in said plug and adopted to come into said recessed neck portion when the plug has been attached, connecting said plug and jack together whereby when said plug is removed the jack will be moved outward to a circuit closing position.
